(57) **CLAIM**

The ornamental design for an optical scanner, as shown in the accompanying drawings and described above.

DESCRIPTION

FIG. 1 is a top, front right perspective view of an optical scanner in accordance with the present invention.

FIG. 2 is a top, rear left perspective view of the optical scanner of FIG. 1.

FIG. 3 is a bottom, front left perspective view of the optical scanner of FIG. 1.

FIG. 4 is a front elevation view of the optical scanner of FIG. 1.

FIG. 5 is a rear elevation view of the optical scanner of FIG. 1.

FIG. 6 is right elevation view of the optical scanner of FIG. 1.

FIG. 7 is left elevation view of the optical scanner of FIG. 1.

FIG. 8 is a top plan view of the optical scanner of FIG. 1; and,

FIG. 9 is a bottom plan view of the optical scanner of FIG. 1.

The broken lines shown herein are for illustrative purposes and form no part of the claimed design.
